US0D1007305S

(12) **United States Design Patent** (10) **Patent No.:** **US D1,007,305 S**
(45) **Date of Patent:** **** Dec. 12, 2023**

(54) **SEALING PLUG FOR BOTTLE CAP**

(71) Applicant: **Shenzhen Fengshun Technology Co., Ltd.**, Shenzhen (CN)

(72) Inventor: **Zefeng Li**, Shenzhen (CN)

(**) Term: **15 Years**

(21) Appl. No.: **29/911,236**

(22) Filed: **Aug. 30, 2023**

(51) **LOC (14) Cl.** 09-07

(52) **U.S. Cl.**

USPC D9/439; D7/396.2

(58) **Field of Classification Search**

USPC D9/499, 434-436, 439; D7/392.1, 396.2
CPC B65D 39/00

See application file for complete search history.

(57) **CLAIM**

The ornamental design for a sealing plug for bottle cap, as shown and described.

DESCRIPTION

FIG. 1 is a perspective view of a sealing plug for bottle cap showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the sealing plug for bottle cap, shown in an open configuration in a configuration of use; and,

FIG. 10 is a perspective view of the sealing plug for bottle cap where the sealing plug for bottle cap is in a configuration of use.

The dash-dash broken lines in the drawings depict portions of the sealing plug for bottle cap that form no part of the claimed design.
